POST CLAMP FOR STORAGE BATTERIES

Robert S. Fennell and Earl E. Spencer,
Norwood, Ontario, CanadaApplication September 14, 1935, Serial No. 40,562
In Canada November 2, 1934

4 Claims. (Cl. 173—259)

The invention appertains to a post clamp of the class that has a slidable jaw urged into clamping engagement with a post of the battery in order to securely attach the clamp and yet enable it to be readily removed upon releasing the pressure-applying element.

The object of the invention is to produce an improved pressure-applying means for the jaw with a view to not only increasing efficiency but 10 also to reduce manufacturing cost.

A further object of the invention is to provide a clamp with a post hole from which the body is laterally elongated in order that the pressure-applying means may be remotely disposed from 15 the post. Both the jaw and the body are cast from a non-corrosive metal. The jaw is moulded to a steel screw-threaded shank on which a nut is engaged and disposed between shoulders on the body for tightening the jaw against the 20 post.

A special feature of the invention is that the body has a jaw-receiving bore upon at its top and a chamber for the shank likewise open at the top. This enables the jaw together with the shank and 25 nut to be readily inserted and removed from the body.

Referring to the accompanying drawing;

Figure 1 is a side elevation of the clamp secured to a post of a storage battery.

Figure 2 is a vertical section of the clamp which is shown on the battery post.

Figure 3 is a plan view of the clamp.

Figure 4 is a cross section taken on line 4—4 of Figure 3.

Figure 5 is a side view of the jaw connected to the screw rod.

Like numerals of reference indicate corresponding parts in each of the figures throughout the drawing of the invention.

In the drawing the reference numeral 1 denotes the conventional storage battery and 8 one of the two posts to which the cable 9 is connected by the clamp. The body 10 extends horizontally 40 from the post as usual and has a vertical hole 11 at one end that loosely receives the post 8, while the other end 12 has the cable 9 attached to it.

The body is cast from a non-corrosive metal 45 and has a jaw receiving bore 13 extending longitudinally from the post hole 11 and communicating with a lengthwise chamber 14 open at the top of the body. The body is fashioned with a pair of ears 15 at opposite sides of the chamber, presenting shoulders 16 substantially spaced from the post hole 11.

An integral lug 17 is spaced from the ears to

supply a nut receiving recess 18. The lug has an aperture 19 in alignment with the chamber aforesaid.

A jaw 20 is slidably disposed in the bore 13 and is preferably of a square cross section as also is the bore in order to preclude relative turning of the jaw in the body. It is obvious, however, that the jaw could be of another non-circular cross section to achieve this end or other means could be substituted to prevent the jaw from turning.

A special feature of the bore structure is that the top wall immediately over the jaw has a lengthwise slot 13' of sufficient width to permit the shank or screw rod to pass therethrough. The slot communicates with the post hole 11 and with 15 the chamber 14, and leaves opposing shoulders 13'' that retain the jaw in the bore.

A screw rod 21 is lodged in the chamber with an end connected to the jaw and the other end freely projecting through the lug aperture. This 20 latter end portion is threaded and a nut 22 is screwed on it and disposed between the ears 15 and the lug 17 so as to be shouldered intermediate thereof. A standard lock washer 22' is fitted back of the nut to prevent it working loose 25 when tightened.

The screw rod is rigidly united to the jaw, preferably in the pouring of the mould from which the jaw is cast.

It will be understood from the preceding description that turning the nut in one direction will feed the screw rod towards the post to urge the jaw into engagement therewith. Turning the nut in the opposite direction withdraws the jaw clear of the post so that the clamp can be removed.

To insert the jaw, screw rod and nut as a unit in the body, the nut is first positioned at the extreme free end of the screw rod. This unit is dropped into the hollow body, the jaw occupying the post hole and the nut being positioned in the 40 recess 18. By screwing the nut further on the rod, the jaw is drawn into the bore to clear the post hole.

Since the clamp body and the jaw are composed of a non-corrosive material they are not affected 45 by the electrolyte. The remote position of the pressure-applying means keeps it clear of the harmful acid. Physical tests have demonstrated that this clamp structure is both practical and satisfactory.

What we claim is:

1. A post clamp comprising an elongated horizontal body having a vertical post hole at an end and a transverse lug at the other end having a hole therethrough, said body having a jaw-receiving

ing bore leading off the post hole and a slotted wall immediately thereover leaving opposing shoulder-forming portions, the body being chambered between the bore and the lug with an open 5 top, the portion of the chamber adjoining the lug being continued into a lateral recess forming shoulders spaced from the inner face of the lug, a jaw slidably mounted in the bore aforesaid, a screw rod rigidly united to the jaw and lodged in 10 the chamber with an end inserted in the hole of said lug, and a nut screwed on the rod and lodged in said recess.

2. In a post clamp, a horizontal elongated body having a vertical post hole at an end thereof and 15 a jaw-receiving bore leading off the post hole, in which a jaw is mountable by inserting it through said post-hole, said body having walls providing a chamber in communication with said bore, a jaw removably mounted in said bore, a screw rod 20 fast thereto and disposed in the chambered part of the body, said jaw and screw rod having an interlocking connection with the body to prevent displacement in normal operation or service, the interlocking connection including shoulders re- 25 taining the jaw in the bore, a hole in a wall of the body in which the free end portion of the screw rod is inserted, and a nut engaged with the screw rod in advance thereof and shouldered in a trans- 30 verse recess supplied by the walls of the body.

3. A post clamp in accordance with claim 2, in

which the body has a slot communicating with the jaw-receiving bore and located immediately thereover so as to enable the screw rod to be inserted and removed as a unit with the jaw.

4. In a post clamp, a horizontal elongated body 5 having a vertical post hole at an end thereof and a jaw-receiving bore leading off the post hole, in which a jaw is mountable by inserting it through said post hole, said body having walls providing a chamber in communication with said bore, 10 a jaw removably mounted in said bore, a screw rod fast thereto and disposed in the chambered part of the body, said jaw and screw rod having an interlocking connection with the body to prevent displacement in normal operation or 15 service, the interlocking connection including an end wall of the body forming a transverse lug and having a hole in which the free end portion of the screw rod is inserted, a nut engaged with the screw rod in advance thereof and shouldered in a 20 recess formed in the body walls so that the screw rod will be axially fed on turning the nut; and a slot formed in the body immediately over the bore and extending thereto, the slot being of a less 25 width than the bore so as to leave shoulders that retain the jaw in place, the slot providing an opening through which the screw rod may be inserted and removed from the body as a unit with the jaw.

ROBERT S. FENNELL.

EARL E. SPENCER.
